ARM SUPPORTING HARNESS

Joseph Ronald Beaton, Dearborn, Mich., assignor
of one-half to Malcolm MacDonald, Dearborn,
Mich.

Application June 25, 1943, Serial No. 492,339

4 Claims. (Cl. 227—49)

This invention relates to arm supports, and its general object is to provide a support in the form of harness that is primarily designed to be worn by artisans whose occupation requires that they grip and hold some implement or the like of their trade for a long period of time in a steady position, such as for example a welder or acetylene torch worker, as my support materially relieves the strain on the arm of the wearer, thus eliminating fatigue and results in greater efficiency, with less effort.

A further object is to provide an arm supporting harness, that can be applied and removed in any easy and expeditious manner, and can be worn by either right or left hand persons, by making a simple change in the arrangement of the parts.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a view of the arm supporting harness which forms the subject matter of the present invention applied to a wearer.

Figure 2 is a plan view of the wristband in open position.

Figure 3 is an edge elevation of the band.

Referring to the drawing in detail, it will be noted that my harness includes a pair of shoulder straps 1 and 2 respectively, for disposal about the shoulders of the wearer at the juncture of the arms therewith, to underlie the arm pits, and while the straps are shown as being of the same width throughout their length, the portions thereof that underlie the arm pits may gradually decrease in width toward the bottoms thereof. In any event, each of the straps have their ends fastened together by a buckle 3 of the pivoted pin type, in the form shown, to adjust the size thereof.

In order to hold the shoulder straps in place, I provide a back strap 4 and a front or chest strap 5, each being identical and the straps 4 and 5 have one of their ends connected to the shoulder strap 2 by snap hooks 6, the hooks being secured to said ends and are attached to rings 7, secured to the straps 2 by loops 8 that are sewed or otherwise fixed to the straps 2. The opposite end portions of the straps 4 and

5 are adjustably fastened to the shoulder strap 1 by buckles 9 of the pivoted pin type, the buckles 9 being secured to the strap 1 by tabs 10 sewed or otherwise fixed to the strap 1. The loops 8 and the tabs 10 are fixed to the shoulder straps slightly above the diametrically opposite sides thereof, as shown. By the construction described, it will be seen that the straps 4 and 5 are detachably connected to the straps 1 and 2 for disposal in bridging relation thereto, and therefore prevent any possibility of casual removal or displacement thereof.

Sewed or otherwise secured to each of the shoulder straps substantially upon diametrically opposite sides thereof are depending tabs 11 having buckles 12 of the pin type secured thereto for adjustably fastening the end portions of a sling strap 12 relative to either of the shoulder straps, the strap 12 having a snap hook 13 slidably mounted thereon, and the strap 12 is shown as being connected to the shoulder strap 1 for use by a right hand wearer, but for a left hand wearer, it will be connected to the shoulder strap 2, as will be apparent.

25 The wristband 14 as best shown in Figures 3 and 4, has a staple member 15 fixed adjacent one end thereof, to be inserted in any one of a row of slots 16 extending along the longitudinal center of the band from adjacent its opposite end, 30 for adjusting the diameter or size of the band, to fit the wrist of the wearer, and the staple is held in one of the slots for securing the band about the wrist, by the snap hook 13 being attached to the staple member 15, as shown in Figure 1. By 35 that construction, it will be seen that the arm of the wearer is amply supported, and as the snap hook 13 is slidably mounted on the strap 12, the latter does not interfere with the free movement of the arm.

40 The band is held in place about the wrist, against sliding movement up the arm, by a looped flexible element 17, such as a rawhide string or the like, the element being adapted for disposal about the thumb and has its ends fixed to the 45 fastening means of the staple member 15. The inner side of the band is preferably covered or lined with a facing strip 18 of felt or the like, to prevent the wrist from becoming chafed.

It will of course be understood that the straps 50 and band can be made from any suitable material, and any type of buckles may be used in place of those shown.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. An arm supporting harness comprising a pair of shoulder straps for disposal about the shoulders of the wearer at the juncture of the arms therewith to underlie the arm pits, a back and a chest strap having their ends connected to the shoulder straps for disposal in bridging relation thereto, a wristband, a looped sling strap having its end portions diverging upwardly for connection to one of the shoulder straps in front and in rear of the shoulder about which it is engaged, and means slidably along the looped portion of the sling strap and detachably connected to the wristband. 10

2. An arm supporting harness comprising a pair of shoulder straps, means for adjustably fastening the ends of each strap together for disposal of the straps about the shoulders of the wearer at the juncture of the arms therewith to underlie the arm pits, a back and a chest strap, buckles secured to one of said shoulder straps for adjustably connecting one of the ends of the back and chest straps thereto, snap hooks secured to the opposite ends of the back and chest straps for detachably connecting the same to the 20 30

other shoulder strap, a wristband, a looped sling strap for the wristband, means for adjustably connecting the sling strap to either of the shoulder straps, and a snap hook slidably mounted on the sling strap and attached to the wristband. 5

3. An arm supporting harness comprising a pair of shoulder straps for disposal about the shoulders of the wearer at the juncture of the arms therewith to underlie the arm pits, a back and a chest strap having their ends connected to the shoulder straps for disposal in bridging relation thereto, a wristband, a staple member fixed to the wristband adjacent one of its ends and said band having a row of slots extending along the longitudinal center thereof from adjacent its opposite end, either of the slots being adapted to receive the staple member therethrough to adjust the size of the band and to secure the same about the wrist of the wearer, a sling strap adjustably connected to one of the shoulder straps, and a snap hook slidably mounted on the sling strap and attached to the staple member to prevent removal thereof from its slot. 15

4. An arm supporting harness comprising the structure of claim 3, a lining for the wristband, and a looped flexible element connected to the wristband for disposal about the thumb of the wearer to prevent the wristband from sliding up the arm. 25

JOSEPH RONALD BEATON.
